3 Claims

This invention in general relates to logic circuits, and in particular, to a high speed-low voltage multivibrator.

In general, transistor multivibrator circuits include first and second transistor stages with suitable feedback arrangements between the stages to achieve desired multivibrator action. Each transistor generally includes a load resistor which in many circuits impairs rise times and reduces the efficiency of the circuit. Accordingly, many multivibrator circuits when fabricated in integrated circuit form have eliminated the conventional load resistors and have replaced them by transistors. Such an arrangement also reduces the power dissipation, a prime consideration in integrated circuits.

Such multivibrators fabricated as integrated circuits maintain fast rise times and high speeds of operation with supply voltages of several volts; however, at lower supply voltages, the counting rates decrease, and if the supply voltage decreases below approximately 1.5 volts, reliable operation may be destroyed.

It is, therefore, one object of the present invention to provide an improved multivibrator circuit which may be designed to operate with extremely small supply voltages.

Another object is to provide a multivibrator having low power dissipation characteristics.

Another object is to provide an extremely reliable multivibrator circuit.

Yet another object is to provide a multivibrator circuit which may be readily fabricated in integrated circuit form.

Briefly, in accordance with the above objects, there is provided a low power logic circuit which includes a first transistor stage having at least a first stage transistor and a second transistor stage having at least a second stage transistor with the first and second transistor stages being cross connected for multivibrator action.

A pair of normally off transistors is provided, each one being uniquely connected to a respective transistor in each stage.

A source of input trigger pulses is provided for selectively and momentarily turning on one transistor of the pair to establish a conductive current path for the transistor to which it is uniquely connected, after which the turned on transistor of the pair reverts to its off condition.

The above stated as well as further objects and advantages of the present invention will become apparent upon reading the following detailed specification taken in conjunction with the drawings, in which:

FIGURE 1 is a circuit diagram of one embodiment of the present invention;

FIG. 2 illustrates in block form input and output connections for the circuit of FIG. 1 to achieve binary action; and

FIG. 3 illustrates the input and output connections of the circuit of FIG. 1 for use as a shift register.

Referring now to FIG. 1, there is illustrated a logic circuit including a first stage having first and second connected transistors Q₁ and Q₂ and a second stage having third and fourth connected transistors Q₃ and Q₄, with suitable feedback or cross coupling arrangements for achieving multivibrator action. By way of example, the collector of transistor Q₂ is connected through the parallel arrangement of resistor R₁ and capacitor C₁ to the base of Q₄, and similarly, the collector of Q₄ is connected to

2

the base of transistor Q₂ through the parallel arrangement of resistor R₂ and capacitor C₂.

The base of transistor Q₁ is connected through resistor R₃ to the collector of transistor Q₄ and the base of transistor Q₃ is connected to the collector of transistor Q₂ through resistor R₄. The junction between PNP transistor Q₃ and NPN transistor Q₄ constitutes a first output terminal Q and the junction between PNP transistor Q₁ and NPN transistor Q₂ constitutes a second output terminal $\bar{Q}$.

The emitters of transistors Q₁ and Q₃ are connected to a source of operating potential V_{cc} and the emitters of transistors Q₂ and Q₄ are connected to a source of reference potential illustrated as ground. In one state of operation, transistors Q₁ and Q₄ are on, while transistors Q₂ and Q₃ are off, and in an opposite state of operation transistors Q₂ and Q₃ are on while transistors Q₁ and Q₄ are off. The circuit thus far described is typical of a prior art multivibrator arrangement. The capability of operating at an extremely low supply voltage V_{cc}, for example in the order of 1.0 to 1.5 volts, is accomplished by the provision of a pair of normally off transistors Q₅ and Q₆ with the collector-emitter current path of transistor Q₅ being ohmically connected to the emitter-base current path of transistor Q₁, and the collector-emitter current path of transistor Q₆ being ohmically connected with the emitter-base current path of transistor Q₃. The emitters of transistors Q₅ and Q₆ are commonly connected to a source of input trigger pulses which includes transistor Q₇ having its base connected to an input differentiation network comprising capacitor C₁ and resistor R₁. The bases of transistors Q₅ and Q₆ form input electrodes RQ and SQ respectively.

In FIG. 2, there is illustrated the circuit of FIG. 1 in block form with suitable connections for a binary counting operation. It is seen that the output terminal $\bar{Q}$ is connected to input terminal SQ and output terminal Q is connected to input terminal RQ. With reference back to FIG. 1, these connections are illustrated by the dotted lines connecting Q and RQ and $\bar{Q}$ and SQ.

To demonstrate the operation of the multivibrator of FIG. 1, an example will be considered wherein the supply voltage V_{cc} is equal to 1.0 volt. Arbitrarily assuming that Q₁ and Q₄ are on, the emitter-base current of transistor Q₁ flowing through resistor R₃ forms the collector current for transistor Q₄, and the collector current of transistor Q₁ flowing through resistor R₁ forms the base current of transistor Q₄. With the low voltage supply, the voltage drop across any on transistor is assumed to be in the order of 0.06 volt; therefore, the output voltage at terminal Q since it is connected to the collector of transistor Q₄ is 0.06 volt and may be considered as a binary ZERO while the voltage at output terminal $\bar{Q}$ is 0.94 volt, that is, the supply voltage minus the voltage drop across transistor Q₁, and may be considered as a binary ONE. The low voltage appearing at the collector of transistor Q₄ is applied to the base of transistor Q₂ and maintains it in a cutoff state and the high voltage appearing at output terminal $\bar{Q}$ insures that transistor Q₃ (since the voltage is coupled to its base) remains in an off condition.

Transistor Q₅ has a low voltage applied to its base from output terminal Q while transistor Q₆ has the higher voltage from output terminal $\bar{Q}$ applied to its base; however, neither transistor Q₅ nor Q₆ is able to conduct since transistor Q₇ is in an off condition.

With the application of an input signal to input terminal C, a differentiation is performed whereby transistor Q₇ receives a positive going spike and then a negative going spike as an input signal. The positive going signal serves to turn on transistor Q₇ thereby dropping the potential at its collector and therefore at the emitters of the transistors

Q_5 and Q_6 . Since a low voltage is applied to the base of transistor Q_5 , only transistor Q_6 will be placed into conduction by the application of the input trigger pulse. The conduction of transistor Q_6 affords a current path for base current to turn on transistor Q_3 . When transistor Q_3 turns on, its collector potential rises toward the supply V_{cc} and this rise in potential is coupled through capacitor C_2 to turn on transistor Q_2 . As transistor Q_2 turns on, the lowering of its collector potential is coupled through capacitor C_1 to the base of transistor Q_4 to cut it off. When the switching action is complete, transistor Q_7 is in a cutoff condition, transistors Q_5 and Q_6 are again non-conducting, and transistors Q_2 and Q_3 are conducting while transistors Q_1 and Q_4 are cutoff, with the output voltage at terminal Q representing a binary ONE and the output voltage at terminal $\bar{Q}$ representing a binary ZERO.

With a high voltage being applied to the base of transistor Q_5 and a low voltage being applied to the base of transistor Q_6 , only transistor Q_5 will conduct upon the application of a subsequent input signal at terminal C to thereby complete a current path for emitter-base current of transistor Q_1 to begin the cumulative action of switching.

The dotted connections in FIG. 1 illustrate the connections to be made for binary counting action. The multivibrator of FIG. 1 finds utility in other arrangements one of which is illustrated in FIG. 3 showing three stages 1, 2 and 3, of multivibrators as illustrated in FIG. 1 together with the proper connections to be made between adjacent stages. Basically, upon the application of an input signal to line C , the information appearing at output terminals Q and $\bar{Q}$ of stage 1 is shifted to stage 2, information in stage 2 is shifted to stage 3 and the information in stage 3 is shifted to a subsequent or output stage not shown.

Accordingly, there has been described a multivibrator circuit which may utilize an extremely low supply voltage while still maintaining proper multivibrator action in providing well defined binary logic signals in response to certain input signal conditions. The high frequency operation of the multivibrator is maintained at the lower supply voltage and extremely low power levels can be attained.

Although the present invention has been described with a certain degree of particularity, it should be understood that the present disclosure has been made by way of example and that modifications and variations of the present invention are made possible in the light of the above teachings.

What is claimed is:

1. A low power logic circuit comprising:
  - (A) a first transistor stage including first and second transistors each having an electrode commonly connected to a first circuit point;
  - (B) a second transistor stage including third and

fourth transistors each having an electrode commonly connected to a second circuit point;

- (C) said first and second transistor stages being cross connected for multivibrator action;
- (D) a first normally off transistor;
- (E) a second normally off transistor;
- (F) the collector of said first normally off transistor being connected to the base of said first transistor;
- (G) the collector of said second normally off transistor being connected to the base of said third transistor;
- (H) the bases of said first and second normally off transistors being for receipt of respective input signals;
- (I) a source of input trigger pulses for selectively and momentarily turning on one of said first or second normally off transistors for establishing a conductive current path for the transistor to which the selectively turned on transistor is connected;
- (J) the emitters of said first and second normally off transistors being connected together;
- (K) said source of input trigger pulses being connected to the commonly connected emitters of said first and second normally off transistors;
- (L) a third normally off transistor connecting the emitters of said first and second normally off transistors with a reference potential; and
- (M) means for momentarily turning on said third normally off transistor.

2. A circuit according to claim 1 wherein:

- (A) output terminals are connected between
  - (1) the first and second transistors; and
  - (2) the third and fourth transistors; and
- (B) the bases of the first and second normally off transistors are connected to a respective one of said output terminals.

3. A circuit according to claim 1 wherein

- (A) the collector of the first normally off transistor is ohmically connected to the base of the first transistor; and
- (B) the collector of the second normally off transistor is ohmically connected to the base of the first transistor.
